1622X

PATENTED DEC. 8, 1911.

J. TRUMAN.
PORTABLE KITCHEN OR CABOOSE.

and 1400 ft. high
A cylindrical furnace to go from the River and making back of the house
a chimney 20 ft. high on the ground. The back door to the main house
by Stable addition or back door.

The furnace is a cylinder of 18 inches in diameter and 82 inches in height, with
a base, and fire on 3 sides riveted to the sides. In the side of the cylinder
there are large holes, to prevent the boiler from being too near the edge, which
would stop the admission of the smoke. The front and lower part of the cylinder
projects out from 16 to 18 inches, and is made flat which forms the fire door and
fire place. The fire place is furnished with a grate for the fuel to lie on the top
of the projection before double doors, the under ones with circular iron
bars in them for the admitting, same bars, or when the bars are thrown up a
bar from the fire place will fit the place, and when closed down, to be
shut down. The same projection rises as high as the top of the fire door,
and a cut for the smoke left through a pipe within two inches of the top
of the cylinder on the opposite side.

The boiler is a coil made to fit the furnace or cylinder, at top rising
and narrowing to the bottom, being about sixteen inches in diameter at top
and 12 inches at the bottom.

There is a receiver about 6 inches long (or more) by 6 inches at top and
narrowing at the bottom to three inches or more, which is fixed on the side
of the boiler, so as to be on a level with the top of the fire door, with pipe
joining the open end being 6 inches or height by one inch and thick in the
center. These pipes are fixed in a vertical position, and the length of them
is enough to project beyond the edge, or side of the bottom of the boiler which
is to be 12 inches high. The furnace and cylinder will stand. There are
two doors to the cylinder, one leading to the chimney, the other leading to the fire door.
